SHOCK ELIMINATING DEVICE FOR
RAILROAD TRACK SCALES

Steve Yuschack, Youngstown, Ohio

Application June 30, 1948, Serial No. 36,130

3 Claims. (Cl. 238—218)

1

This invention relates to rail joints, particularly joints for easing shocks of car wheels traversing approaches to track scales and the like.

An object of the invention is to provide improved rail joints which include means bridging the gaps at such approaches and thereby gradually and smoothly transferring weight of car wheels across these gaps.

A further object of the invention is to provide improved rail joints for such approaches in which the gaps are bridged by bars pivoted to the inside of one set of rails and cushioned against the other rails, thereby transferring the weight of car wheels gradually and smoothly from one set of rails to the other.

A further object of the invention is to provide improved rail joints which ease shocks, and yet do not increase the length of gaps between rails nor necessitate cutting away the rail heads.

In accomplishing these and other objects of the invention, I have provided improved details of structure, a preferred form of which is shown in the accompanying drawing, in which:

Figure 1 is a top plan view of an improved rail joint embodying features of the present invention;

Figure 2 is a side elevational view of the rail joint; and

Figures 3 and 4 are vertical sectional views taken substantially on lines III—III and IV—IV respectively of Figure 1.

Referring more in detail to the drawing:

The rail joint of the present invention is illustrated on the approach to a track scale. The scale has a platform 10 which moves vertically in accordance with loads applied thereto and hence must be free of its approaches. The approach includes a fixed foundation 12. Rails 13 are supported on foundation 12 and rails 14 on platform 10, only one rail of the track being illustrated. The rail ends are separated by a gap G, which is necessary to permit free vertical deflection of the scale platform, as indicated in Figure 2.

In accordance with the present invention, a bridge bar 15 is pivotally mounted on the web of approach rail 13 and extends past the gap inside and closely adjacent the rails. The mounting preferably comprises a supporting plate 16 which carries an integral bearing 17 having an upstanding apertured ear portion 18. The rail flange is cut away to accommodate the bearing, as best shown in Figures 1, 3 and 4. The bearing furnishes an arcuate foundation on which the pivot end of the bridge bar bears. A bolt 55

2

19 passes through ear 18, bridge bar 15 and the web of rail 13, and is affixed by a nut 20, spacers 21 being interposed alongside the web (Figure 3). The bolt, nut and spacers maintain the bridge bar in proper relation to the rail flange and the supporting plate, but the bolt does not carry any of the weight of the bridge bar. Such weight is borne directly by bearing 17.

Beyond the pivotal connection to the approach rail, the bridge bar has a stop 22 which is between the head and the flange of the approach rail and engageable with the head to limit pivotal movement of the bridge bar (Figure 4). The contour of the upper face of said stop preferably matches that of the underface of the rail head to facilitate this engagement. The bridge bar has a downwardly directed bore 23. A compression spring 24 bears between the end of the bore and the top of supporting plate 16 and cushions the bridge bar and urges it upwardly to the limit permitted by engagement of stop 22 with the rail head (Figures 2 and 4).

An integral guide and bumper 25 is supported on platform 10 adjacent the end of rail 14 and has an upstanding flange 26. The guide and bumper receive the free end of the bridge bar. Since spring 24 urges the bridge bar upwardly, the free end normally clears bumper 25. Therefore the bridge bar does not impose a load on the scale.

The upper face of bridge bar 15 is convex in side elevation (Figure 2). The inner edge of the top face has a lip 27 for retaining flanges of car wheels W (Figures 3 and 4).

In operation, as car wheels W approach the scale, they first engage bridge bar 15 a little beyond its pivot point and ride up its convex surface. Such engagement compresses spring 24 and the free end of the bridge bar contacts bumper 25 and part of the weight applied to the bridge bar is transferred to platform 10 via the bumper. As the wheel moves forward, an increasing portion of its weight thus is transferred to the scale platform. By the time the wheel actually crosses the gap, the greater part of its weight already has been transferred. After the wheel rides free of the bridge bar, spring 24 lifts the bridge bar out of contact with the bumper. The reverse of such weight transfer takes place when the wheel is removed from the scale.

From the foregoing description, it is seen that I have provided a rail joint in which weight of car wheels is transferred gradually and smoothly

between the rail ends. Thus shocks of car wheels traversing these gaps are effectively eliminated.

While I have shown and described only a single embodiment of the invention, it is apparent that modifications may arise. Therefore, I do not wish to be limited to the disclosure set forth but only by the scope of the appended claims.

I claim:

1. A rail joint for easing shocks of car wheels traversing gaps between rails at approaches to track scales and the like comprising a bridge bar, a bearing fixed with respect to the approach rail, means pivotally attaching said bridge bar to said bearing and to the web of the approach rail, said bearing having an arcuate recess which receives the pivot end of the bar to furnish a foundation therefor, said bar extending past the gap inside and closely adjacent the rails, a stop fixed to said bar between the head and the flange of the approach rail and engageable with the head to limit pivotal movement of the bar, said bar having a downwardly facing bore, a compression spring in said bore bearing against the approach rail support and urging said stop into engagement with the rail head, and bumper means fixed with respect to the other rail, the free end of said bar being adapted to rest on said bumper means on application of a load to said bar.

2. A rail joint for easing shocks of car wheels traversing gaps between rails at approaches to track scales and the like comprising a bridge bar, a bearing fixed with respect to the approach rail, means pivotally attaching said bridge bar to said bearing and to the web of the approach rail, said bearing having an arcuate recess which receives the pivot end of the bar to furnish a foundation therefor, said bar extending past the gap inside and closely adjacent the rails, the upper face of said bar being convex in side elevation and having a lip alongside the rail heads and being adapted to receive and support the weight of car wheels traversing the gap, a stop fixed to said bar

between the head and the flange of the approach rail and engageable with the head to limit pivotal movement of the bar, spring means acting on said bar and urging said stop into engagement with the rail head, and bumper means fixed with respect to the other rail, the free end of said bar being adapted to rest on said bumper means on application of a load to said bar.

3. A rail joint for easing shocks of car wheels traversing gaps between rails at approaches to track scales and the like comprising a bridge bar, a bearing fixed to the approach rail foundation and having an arcuate recess receiving a complementary end portion of said bar, a bolt pivotally attaching said bar to said bearing and to the web of the approach rail, said bearing furnishing a foundation for the pivot end of said bar and transmitting forces applied to the bar directly to the approach rail foundation, said bar extending past the gap inside and closely adjacent the rails, a stop fixed to said bar between the head and the flange of the approach rail and engageable with the head to limit pivotal movement of the bar, said bar having a downwardly facing bore, a compression spring in said bore bearing against the approach rail foundation and urging said stop into engagement with the rail head, and bumper means fixed with respect to the other rail, the free end of said bar being adapted to rest on said bumper means on application of a load to said bar.

STEVE YUSCHACK.
